AUTOMATIC RAZOR EDGING MACHINE

Arthur J. Holman, Brookline, Mass.

Application November 4, 1929, Serial No. 404,713

16 Claims.

(Cl. 51—40)

My invention relates particularly to a device for sharpening the edges of double-edge wafer razor blades and it has been the special object of my invention to provide a device wherein the 5 separate blades may be fed continuously and automatically toward and into operative contact with abrading members along a straight and uninterrupted path, thereby permitting the use of several abrasive surfaces, of progressively finer grain, along the path so as to eliminate the 10 individual handling of the separate blades heretofore found necessary to apply the blades successively to different machines for grinding, honing and stropping, or to the same machine to 15 treat successively both edges. It has also been the object of my invention to so organize and construct my device that the full advantage of the fundamentally basic principles of abrading, disclosed in my copending patent applica- 20 tion, Serial No. 342,387, filed February 25, 1929, may be utilized in association with a continuous non-periodic blade feeding mechanism, thus ex- 25 tending the practical application of these prin- ciples to the commercial manufacture of razor blades. I have sought to accomplish this re- 30 sult by a device which shall be efficient, simple, compact and economical to operate.

My device may be best understood by reference to the accompanying drawings in which

30 Fig. 1 is a front view of my device.

Fig. 2 is a plan view of my device somewhat enlarged in scale as compared with Fig. 1.

Fig. 3 is an enlarged front view of an abrading roller showing the rectangular drive shaft 35 used when the roller is employed in the lower position and the attached gear for operating an associated roller.

Fig. 4 is an end view of the roller shown in Fig. 3 displaying the means for assembling the 40 roller and attaching the abrading material.

Fig. 5 is an end view of a lower roller drive gear and shaft.

Fig. 6 is a side view of the gear and shaft shown in Fig. 5.

Fig. 7 is an enlarged end view of my device with the base and feed belt pulleys removed, illustrating the position of a blade when being sharpened with respect to a pair of associated 50 abrading rollers.

Fig. 8 is a much enlarged side view of a portion of the metallic feed belt.

Fig. 9 is a cross-sectional view on line 9—9 of Fig. 8.

Fig. 10 is a top view of a portion of the feed

belt with a razor blade, indicated by broken lines, mounted thereon.

Referring now more specifically to the drawings, upon which like reference numbers indicate like parts, 1 is a base (Fig. 1) the top of which is covered by a bed plate 2 attached thereto by means of the screws 3 (Fig. 2). The base 1 is provided with a boss 4 to which is attached by means of the screws 5 the forked bracket 6 in the ends of which is journaled the shaft 7 of the pulley 8. The base 1 is also provided with bosses 9 upon which is mounted the forked bracket 10 between the forked ends of which is pivoted an upright forked arm 11 in the upper extremities of which is journaled the shaft 12 of the pulley 13. A thin flexible steel feed belt 14 is mounted on the pulleys 8 and 13. A rod 15 screwed into boss 16 on the upright forked arm 11 has attached to its free end one end of the coil spring 17, the other end of which is attached to a post 18 screwed into the bed-plate 2.

The tension of the spring 17 tends to elevate the rod 15 and rock outwardly the upright forked arm 11 bearing the pulley 13, thereby maintaining suitable tension on the feed belt 14. This feed belt 25 14 is provided on each side with integral annular bosses 19 (Figs. 8, 9 and 10) the sides of which are slightly flattened to conform to the shape of the end perforations of a standard double edge wafer razor blade. Thus a razor blade 20 may 30 be supported and retained on the outer surface of the feed belt 14 by the bosses 19 on that surface while the bosses 19 on the under surface fit into suitable pockets 21 in the faces of pulleys 8 and 13.

To provide and maintain the proper alignment of the feed belt 14 and the blades 20 thereon during the period of contact of the blades with the abrading means later to be described, I have provided a pair of associated guide plates 22 and 23 (Figs. 2 and 7) which are held together by screws 24 and attached by screws 25 to a supporting frame 26 mounted by means of screws 27 on the bed-plate 2, and also a second pair of associated guide plates 28 and 29 which are held 40 together by screws 30 and attached by the screws 31 to a supporting frame 32.

It will be observed that the pairs of associated 50 guide plates 22 and 23 and 28 and 29 are supported respectively on opposite sides of the feed belt 14 in such a manner that one edge of a blade mounted on the belt 14 projects beyond one pair of guide plates whereas the opposite edge of the blade projects beyond the other pair of guide plates. The associated faces of the guide plates 55

22 and 23 and 28 and 29 are so shaped as to provide suitable clearance for the feed belt 14 and the annular bosses 19 thereon and the blades 20 (see Fig. 7.) This clearance is greatly increased 5 along the path of the edge of the blade which is not being operated upon so as to avoid any damage to an edge of the blade, and a very slight clearance is provided for the sides of the bosses 19.

A bracket 33 is attached by screws 33a to the 10 top of bed-plate 2. This bracket 33 is provided with guideways 33' and 33'' which fit respectively into V grooves in projections 34 and 35 on the sliding carriage 36. A bracket 37 similar to bracket 33 is mounted on the side of the machine 15 opposite to that on which the bracket 33 is mounted by means of screws 38 entering the bed-plate 2. The bracket 37 carries the sliding carriage 39 which is provided with V grooves in projections 40 and 41 into which fit respectively 20 the guideways 42 and 43 on the bracket 37.

Within each of the sliding carriages 36 and 39 25 is mounted a pair of abrading rollers comprising upper rollers 44 and lower rollers 45. A typical abrading roller is illustrated in Figs. 3 and 4. Each roller comprises an eccentric hub 46 having offset lugs 47 to which is attached by means of screws 48 a frame 49 for supporting the abrading materials 50, 51 and 52 of progressively varying grain. The frame 49 is provided with a curved surface 53 centered on an axis which is preferably slightly displaced from the axis of rotation of the roller. In Fig. 4 the axis of rotation is indicated by the intersection of the broken lines a—a and b—b, whereas the axis of the curved surface 53 is indicated by the intersection of the broken line a—a with the solid line c—c. The frame 49 is provided with radial shoulders 54 to which are clamped by the plates 55 and screws 56 the ends of the abrading materials 50, 51 and 52. The rollers are provided with a shaft 57 which is press-fitted into the eccentric hub 46. The shaft 57 has press-fitted thereon a gear 58. The shaft 57 is provided with portions 59 of reduced diameter which fit into ball bearings 60 carried in the ends of the sliding carriages 36 and 39. Upper rollers 44 have the shaft 57 cut off at the point indicated by the broken line d—d of Fig. 3, whereas the shafts of the lower rollers 45 are provided with a rectangular projection 61 for a purpose to be hereinafter specified.

Mounted transversely on the bed-plate 2 by means of screws 62 is a bearing bracket 63 provided with a pair of opposite integral housings 64 to contain bearings in which are journaled the main drive shaft 65 upon which are press-fitted the helical gears 66 and 67, and also the grooved crank wheels 68 and 69 to which are attached respectively the connecting rods 70 and 71 which are attached to the sliding carriages 39 and 36 respectively.

The bearing bracket 63 is also provided with a second pair of opposite integral housings 72 to contain bearings in which is journaled the shaft 73 upon which is press-fitted the helical gear 74 which meshes with the helical gear 66 on the main drive shaft 65.

The shaft 73 is provided with a rectangular hole 75 within which the rectangular shaft extension 61 of the shaft 57, of the lower roller mounted in sliding carriage 39, is a free sliding fit.

The bearing bracket 63 is also provided with a third pair of opposite integral bearing housings 76 to contain bearings in which is journaled a shaft 77 similar to shaft 73. This shaft 77 car-

ries press-fitted thereon a helical gear 78 which meshes with helical gear 67 on the main drive shaft 65. A rectangular shaft extension 61 of the shaft 57 of the lower roller carried by the sliding carriages 36 is a free sliding fit in the rectangular hole through the shaft 77.

The upper rollers 44 are each driven by its associated lower roller 45 through a gear 58 meshing with a like gear on the upper roller.

A shaft 79 (Fig. 1) journaled in the forked bracket 6 carries fast on one end a pulley 80 and on the other end a worm 81 which meshes with a worm wheel 82 fast mounted on one end of a shaft 83 journaled in a bracket 84 mounted on the forked bracket 6. The other end of the 15 shaft 83 carries fast mounted thereon a worm 85 which meshes with a worm wheel 86 fast mounted on one end of the shaft 37, which is journaled in a boss 88 on the forked bracket 6 (Fig. 2). Fast mounted on the other end of the 20 shaft 37 is the spur gear 89 which meshes with the gear 90 fast mounted on shaft 7. A suitable flexible belt 91 transmits power from the grooved crank wheel 68, on the main drive shaft 65, to the pulley 80 on the shaft 81.

25 The operation of my device is as follows:

Wafer razor blades provided with the usual perforations are placed upon the feed belt 14, the lugs 19 of which engage the perforations. The blades are successively placed on the horizontal portion of the feed belt 14 above the pulley 13. This may be done by hand or by a suitable automatic mechanical means. Power from a suitable source is then applied to the grooved crank wheel 68 thus rotating the main drive shaft 65 and the 35 crank wheel 68 mounted thereon. The sliding carriages 36 and 39 are thus given a reciprocating motion through their crank connections with the crank wheels 68 and 69. This motion is along a path parallel to that of the feed belt 14 as 40 it passes through the associated guide plates 23 and 29 and 22 and 23.

The lower abrading rollers 45 are caused to rotate by the engagement of their rectangular shaft extensions 61 in the rectangular holes 75 45 within the shafts 73 and 77 whereon are mounted respectively the helical gears 74 and 78, which mesh respectively with helical gears 66 and 67 fast mounted on the main drive shaft 65. The upper abrading rollers 44 are driven through 50 their attached gears 58 which mesh with the corresponding gears on the associated lower roller. It is to be noted from Fig. 7 that the upper roller 44 and its associated lower roller 45 are initially positioned in such a way that as they 55 rotate each presents clearance space for the abrading surface of the other. The gear ratios between the main drive shaft and the lower roller driving means are such, preferably, that the cycle of reciprocation of the roller carriages 36 and 39 60 differs in frequency from the cycle of rotation of the abrading rollers.

The feed belt 14 is caused to travel so as to bring the blades thereon mounted successively into operative position, first between the associated guide plates 23 and 29, and then between the associated guide plates 22 and 23, in the following manner:

The belt 91 transmits the rotative influence of crank wheel 68 to the pulley 80 and its attached shaft 79 and the worm 81 which in turn rotates the worm wheel 82. Power is thence transmitted through the shaft 83 to the worm 85 which rotates the worm wheel 86 attached to shaft 87 which carries the gear 89 meshing with gear 90 on the 75

5 pulley 8. Rotation of the pulley 8 causes the feed belt 14 to travel by means of the engagement of the bosses 19 with the pockets 20 in the face of the pulley 8. The above-described reduction gears provide a relatively slow rate of feed belt travel as compared with the speed of reciprocation and rotation of the abrading rollers.

10 As the blades come successively into that part of their path of travel which lies opposite the first encountered pair of associated abrading rollers they are constrained to travel in a straight path notwithstanding the stresses of the abrading process by means of the associated guide plates 28 and 29 which so hold the blade as to present 15 its left edge to the abrading rollers which alternately engage the top and bottom beveled surfaces of the left edge of the blade with sufficient force to flex the blade thus held against rocking. It will be apparent that the blade will be held 20 against vertical displacement by the contact of the combined belt and blade with the upper and lower faces of the associated guide plates, and will also be held against lateral displacement by the contact of the sides of the bosses 19 with the 25 side walls of the channels in the guide plates through which these bosses pass. Further progress of the blades through the machine will bring them successively under the influence of the second pair of associated abrading rollers 30 in which position they are guided and supported by the associated guide plates 22 and 23 which present the right edges of the blades to the abrading rollers in the same manner as above described. As the blades emerge from between 35 the associated guide plates 22 and 23, they may be removed from the feed belt 14 by hand or by any suitable automatic means.

40 From the above description of my device, it will be apparent that it possesses the advantage of great simplicity and uninterrupted continuity 45 of action without steps in the handling of individual blades which consume time or require the attention of a machine tender. The flow of blades through the machine is continuous and effective for performing each and every function in the edging process.

45 Although I have described my device as comprising one unit of oppositely placed stropping rollers for operating upon the right and left edges of the blades in one passage through the machine, it is apparent that a longer feed belt 50 may be provided and successive units for grinding and honing, as well as stropping, may be located along the path of feed by increasing the number 55 of the sliding carriages with their associated rollers and accompanying actuating parts, and oppositely placed guide members, all similar to those above described, excepting as to the character of 60 abrading surface provided for the abrading rollers. Thus all operations for edging the blades 65 may be performed successively and continuously in a single machine, thereby saving much time and labor in the manufacture of the wafer type of razor blade. By providing a feed or path of travel for the blades which is along the abrading members, it becomes possible to employ abrading 70 members, the surfaces of which are progressively finer thereby effecting a gradual abrasion of the beveled blade surfaces such as to avoid the probability of deep scratching which may overrun and affect the ultimate edge of the blade. An edge so progressively formed is little likely to develop a "feather". This is especially true when full 75 advantage is taken of the unique abrading features made available by properly relating the

speed of rotation of the abrading members to the speed at which they are reciprocated. The relative frequencies of rotation and reciprocation are established by the gear ratios, which should be such as to provide a large maximum, and rapidly changing, angle of abrasion, and a maximum variation in path, upon the abrading surface, traversed by unit areas on the beveled surfaces of the blades. The principles involved and the advantages resulting therefrom are fully described 10 and claimed, as applied to a portable stropping device, in my co-pending patent application, Serial No. 342,387, filed February 25, 1929.

15 The abrading rollers are freely removable for the purpose of renewing the abrading material 15 thereon by disengaging the connecting rod which operates the sliding carriage wherein the rollers are mounted, and sliding the roller carriage off its guideways. Access may then be had through the open side of the carriage to the screws 48 20 which retain the frame 49 supporting the abrading material.

25 In the above mentioned co-pending patent application there is disclosed new and basic principles for stropping razor blades and therein is 30 illustrated a portable stropping device embodying these principles. The present device, embodying additional novel features, which make it exceptionally convenient and economical in operation, represents the preferred form of a commercial blade manufacturing machine employing 35 these basic principles. The combined reciprocating and rotative movements of the abrading members, incorporated in my device, provide the means essential to the accomplishment of those 40 functions best adapted to produce superior cutting edges of maximum uniformity. The essential feature of the present invention is the adaptation of a continuous non-periodic blade feeding mechanism to a device arranged to grind and 45 polish the beveled surfaces on blades in the manner described. Another important feature is that the device is constructed in such a way that all edging operations, including grinding, honing and stropping, may be performed on both edges of 50 a blade during one continuous passage of the blade through the machine. Hence my device is 55 convenient and economical in operation, and possesses the characteristics essential to the production of the highest quality and most uniform cutting edges.

55 Having thus fully described my invention, what I claim is:

1. In a device of the character specified, the combination of means whereon a blade may be 60 mounted, slidably mounted carriages supporting 65 rotatable abrading means, means for so supporting and advancing said means whereon the blade may be mounted that the blade may be presented to said rotatable abrading means along a path of travel substantially parallel to the axis of rotation of said abrading means, and means for reciprocating said slidably mounted carriages along 70 said axis simultaneously with the rotation of said abrading means.

75 2. In a device of the character specified the combination of a belt whereon a blade may be mounted, bosses on said belt adapted to engage holes in said blade, means for actuating said belt, a pair of associated guide members arranged to partly embrace said belt and the blade mounted thereon in a manner whereby one edge of the blade projecting beyond said guide members throughout their entire length may be maintained in exact alignment, and a rotatable

abrading member slidably mounted beside said belt and arranged to rotate about, and reciprocate along, an axis substantially parallel thereto and adapted to engage the projecting edge of the blade carried thereby.

3. In a device of the character specified the combination of a belt whereon a blade may be mounted, bosses on said belt adapted to engage holes in said blade, means for actuating said belt, a pair of associated guide members arranged to partly embrace said belt and the blade mounted thereon in a manner whereby one edge of the blade projecting beyond said guide members throughout their entire length may be maintained in exact alignment, and a pair of associated rotatable abrading members slidably mounted beside said belt and arranged to rotate each upon an axis substantially parallel to said belt and to reciprocate each along its axis of rotation, and adapted to engage alternately in rapid succession the upper and lower beveled faces of the projecting edge of the blade carried by said belt.

4. In a device of the character specified the combination of a belt whereon a blade may be mounted, bosses on said belt adapted to engage holes in said blade, means for actuating said belt, a first pair of associated guide plates arranged to partly embrace said belt and the blade mounted thereon in a manner whereby one edge of the blade projecting beyond said guide plates may be maintained in exact alignment, a second pair of associated guide plates arranged to partly embrace said belt and the blade mounted thereon at a stage of its travel beyond said first pair of guide plates in a manner whereby the other edge of the blade projecting beyond said second pair of guide plates may be maintained in exact alignment, a rotatable abrading member slidably mounted beside said belt on one side thereof and arranged to engage the beveled surface of that edge of the blade which projects beyond said first-mentioned pair of guide plates, a second rotatable abrading member slidably mounted beside said belt on the side thereof opposite to that on which said first-mentioned abrading member is mounted and arranged to engage the beveled surface of that edge of the blade which projects beyond said second pair of guide plates, and means for rotating and simultaneously reciprocating said abrading members along paths parallel to said belt.

5. In a device of the character specified the combination of a belt whereon a blade may be mounted, bosses on said belt adapted to engage holes in said blade, means for actuating said belt, a first pair of associated guide plates arranged to partly embrace said belt and the blade mounted thereon in a manner whereby one edge of the blade projecting beyond said guide plates may be maintained in exact alignment, a second pair of associated guide plates arranged to partly embrace said belt and the blade mounted thereon at a stage of its travel beyond said first pair of guide plates in a manner whereby the other edge of the blade projecting beyond said second pair of guide plates may be maintained in exact alignment, a rotatable abrading member slidably mounted beside said belt on one side thereof and arranged to engage the beveled surface of that edge of the blade which projects beyond said first-mentioned pair of guide plates, a second rotatable abrading member slidably mounted beside said belt on the side thereof, opposite to that on which said first-mentioned abrading member is

mounted and arranged to engage the beveled surface of that edge of the blade which projects beyond said second pair of guide plates, and means whereby said slidably mounted rotatable abrading members may be reciprocated each along a path of travel substantially parallel to said belt.

6. In a device of the character specified the combination of a frame, a pair of oppositely placed pulleys mounted on said frame, a flexible feed belt mounted on said pulleys, bosses on said belt whereon blades may be mounted, means for actuating one of said pulleys, two pairs of associated guide plates, each pair arranged to embrace said belt and blades carried thereon in such a manner as to maintain exact alignment of said blades as said belt feeds said blades between said guide plates, one pair of said guide plates being mounted on one side of said frame and arranged to expose one edge of a blade passing under its influence and the other pair of said guide plates being mounted on the other side of said frame and arranged to expose the other edge of a blade passing under its influence, a pair of slidable carriages each of which is mounted on said frame opposite a pair of associated guide plates, rotatable abrading means mounted within said carriages, means for reciprocating said carriages, and means for rotating said abrading means.

7. In a device of the character specified the combination of a frame, a pair of oppositely placed pulleys mounted on said frame, a flexible feed belt mounted on said pulleys, bosses on said belt whereon blades may be mounted, means for actuating one of said pulleys, two pairs of associated guide plates, each pair arranged to embrace said belt and blades carried thereon as said belt passes between said guide plates, one pair of said guide plates being mounted on one side of said frame and arranged to expose one edge of a blade passing under its influence and the other pair of said guide plates being mounted on the other side of said frame and arranged to expose the other edge of a blade passing under its influence, a pair of slidable carriages each of which is mounted on said frame opposite a pair of associated guide plates, rotatable abrading means mounted within said carriages, means for reciprocating said carriages and means for rotating said abrading means, said reciprocating means and said rotating means comprising a main drive shaft rotatably mounted in said frame at right angles to said feed belt and between said slidable carriages, a pair of crank wheels fast mounted on said main drive shaft, a pair of connecting rods each of which connects one of said sliding carriages to a crank wheel, a pair of opposite hand helical gears fast mounted on said main drive shaft, a pair of auxiliary drive shafts each rotatably mounted at right angles to said main drive shaft, a pair of helical gears each mounted on one of said auxiliary drive shafts and arranged to mesh with one of said helical gears on said main drive shaft, a lower abrading roller rotatably mounted in each slidable carriage, a shaft extension projecting from said lower roller and slidable within one of said auxiliary shafts and adapted to be rotated thereby, a gear fast mounted on said lower roller, an upper roller rotatably mounted in each slidable carriage, a gear fast mounted on said upper roller and arranged to mesh with said gear fast mounted on said lower roller.

8. In a device of the character specified, the combination of a feed belt provided with means

for supporting double-edge blades mounted thereon, means for constraining said belt and double-edge blades mounted thereon to travel in a fixed path notwithstanding abrading stresses thereon, two pairs of associated slidably mounted rotatable abrading members located each on an opposite side of said feed belt and adapted to operate alternately in rapid succession on the upper and lower beveled surfaces of opposite edges of double-edge blades mounted on said feed belt, and means for simultaneously actuating said pairs of abrading members, both as to reciprocation and rotation.

9. In a device of the character specified, the combination of a feed belt provided with means for supporting blades mounted thereon, means for constraining said belt and blades mounted thereon to travel in a fixed path notwithstanding abrading stresses thereon, a pair of associated slidably mounted rotatable abrading members located beside the path of travel of said feed belt and adapted to operate alternately in rapid succession in the manner specified, upon the beveled surfaces adjacent an edge of a blade mounted thereon, said abrading members being provided with a semi-cylindrical abrading surface the fineness of which increases in the direction of travel of said feed belt, and means for simultaneously actuating said abrading members, both as to reciprocation and rotation.

10. In a device of the character specified, the combination of a continuous non-periodic blade feeding mechanism adapted and arranged to expose simultaneously to alternate abrading action both beveled surfaces adjacent one edge of blades being fed thereby, and an abrading mechanism providing combined reciprocating and rotary movement of abrading members having substantially semi-cylindrical abrading surfaces, said abrading mechanism being adapted and arranged to grind and polish the beveled surfaces of blades continuously and progressively fed through said abrading mechanism by said blade feeding mechanism.

11. In a device of the character specified, the combination of a continuous non-periodic blade feeding means, means adapted and arranged to continuously maintain exact alignment of blades being fed by said blade feeding means notwithstanding alternate abrading of each beveled surface adjacent one edge of said blades, and an abrading mechanism providing combined reciprocating and rotary movement of substantially semi-cylindrical abrading members, said abrading mechanism being adapted and arranged to grind and polish the beveled surfaces of said blades as they are progressively and continuously fed through said abrading mechanism.

12. In a device of the character specified, the combination of a continuous blade feeding mechanism, and an abrading mechanism including a plurality of substantially semi-cylindrical abrading members provided with combined reciprocating and rotary movement, said abrading members being adapted to grind and polish the beveled surfaces of blades continuously and progressively fed past said abrading members, and means

for rotating and simultaneously reciprocating said abrading members along axes parallel to the path of travel of said blades.

13. In a device of the character specified, the combination of a continuous blade feeding mechanism, and an abrading mechanism including a plurality of substantially semi-cylindrical abrading members provided with combined reciprocating and rotary movement, said abrading members being adapted to grind and polish the beveled surfaces of blades continuously and progressively fed past said abrading members, and means for rotating, at one frequency, and simultaneously reciprocating, at a different frequency, said abrading members along axes parallel to the path of travel of said blades.

14. In a device of the character specified, the combination of a continuous non-periodic blade feeding mechanism, an abrading mechanism including a plurality of eccentrically mounted substantially semi-cylindrical abrading members provided with combined reciprocating and rotary movement, said abrading members being adapted to contact, intermittently and under periodically varying pressure, with the beveled surfaces of blades as they are progressively fed past said abrading members, and means for rotating, at one frequency, and simultaneously reciprocating, at a different frequency, said abrading members along axes parallel to the path of travel of said blades.

15. In a continuous blade feeding mechanism, the combination of a thin flexible belt having integral bosses projecting therefrom, said bosses being formed and spaced to so fit into perforations in a blade to be fed by said blade feeding mechanism, that said blade is, for all practical purposes, doweled to said belt, and a pair of associated guide plates arranged and adapted to embrace said belt and said integral bosses, together with said blade, in such a manner that the edge of said blade projecting beyond said guide plates throughout their entire length may remain substantially parallel to said guide plates notwithstanding alternate abrading of each beveled surface adjacent said edge, and the portion of said blade within said guide plates may be held against lateral and vertical displacements and may have no freedom of motion with respect to said guide plates except in one direction, namely along the path of travel of said belt.

16. In a device of the character specified, the combination of a continuous non-periodic blade feeding mechanism arranged to handle double edge wafer blades, said mechanism including means for so guiding and supporting said blades that both edges of said blades may be finished in one passage through said device and both beveled surfaces adjacent one edge thereof may be ground or polished simultaneously, and rotatable abrading members having substantially semi-cylindrical abrading surfaces, said abrading members being adapted and arranged to engage alternately in rapid succession first one and then the other of the beveled surfaces adjacent one edge of said blades.

ARTHUR J. HOLMAN.
